DESIGN FOR A TOOTH BRUSH HOLDER

Carmelo D'Angelo, Buffalo, N. Y.

Application October 29, 1945, Serial No. 123,297

Term of patent 7 years

(Cl. D4—3)

To all whom it may concern:

Be it known that I, Carmelo D'Angelo, a citizen of the United States, residing at Buffalo, in the county of Erie and State of New York, have invented a new, original, and ornamental Design for a Tooth Brush Holder, of which the following is a specification, reference being had to the accompanying drawings, forming part thereof.

In these drawings:

Fig. 1 is a perspective view of the tooth brush holder viewed from the front side thereof.

Fig. 2 is a similar view viewed from the rear side of the same.

Fig. 3 is a bottom plan view of the holder.

Fig. 4 is a top plan view of the same.

Fig. 5 is a perspective view of the upper and lower sections of the tooth brush holder body in a separated condition.

I claim:

The ornamental design for a tooth brush holder, substantially as shown.

CARMELO D'ANGELO.
